CLAIM

What is claimed is the ornamental design for a display screen with graphical user interface, as shown and described herein.

DESCRIPTION

FIG. 1 is a front view of a display screen with graphical user interface, showing a first embodiment of the new design; and,

FIG. 2 is a front view of a second embodiment thereof. The broken line showing of the display screen and graphical user interface are included for the purpose of illustrating environmental structure and portions of the article and form no part of the claimed design.
